BY

Victor J. Evans ATTORNEY.

UNITED STATES PATENT OFFICE.

BEY A. WISE, OF VINCENNES, INDIANA.

DESIGN FOR A TOWER-MONUMENT.

55,920.

Specification for Design.

Patented July 20, 1920.

Application filed January 10, 1920. Serial No. 350,709. Term of patent 7 years.

To all whom it may concern:

Be it known that I, BEY A. WISE, a citizen of the United States, residing at Vincennes, in the county of Knox and State of Indiana, have invented a new, original, and ornamental Design for a Tower-Monument, of which the following is a specification, reference being had to the accompanying drawing, forming a part thereof.

The figure is a perspective view of the tower showing my new design.

The ornamental design for a tower monument as shown.

MRS. BEY A. WISE.
